UNITED STATES PATENT OFFICE.

DAVID ROUSSEAU, OF NEW YORK, N. Y.

ELECTRIC GAS-LIGHTING DEVICE.

SPECIFICATION forming part of Letters Patent No. 400,492, dated April 2, 1889.

Application filed July 6, 1888. Serial No. 279,176. (No model.)

To all whom it may concern:

Be it known that I, DAVID ROUSSEAU, a citizen of the United States, residing in New York, county of New York, and State of New York, have invented a new and useful Improvement 5 in Electric Gas-Lighting Devices, of which the following is a specification.

My invention relates to improvements in gas and other lighting devices where the act of ignition is brought about by creating an electric spark in the vicinity of the gas; and to this end it consists, first, in a novel arrangement of parts adapted to turn on and light the gas at one act, said parts being so compactly arranged 10 as to be concealed beneath an imitation candle or shield; second, it consists in details of construction hereinafter described, and particularly pointed out in the claims which follow this specification.

20 The invention will be fully understood by referring to the accompanying drawings, in which—

Figure 1 is a side elevation of a well-known form of candle gas-burner, the candle-shield being partly broken away to show my improved attachments. Fig. 2 is a vertical sectional view showing the apparatus entire, and Fig. 3 is a plan view as seen looking into the upper end of the candle attachment.

30 A is a gas-burner fixed in the usual manner to the burner-pipe.

B is a conducting yoke or collar insulated from the burner-tip a, and carrying a fixed electrode, b, located in close proximity to the 35 gas-jet.

c is a metallic wiping-electrode, which plays loosely through a hole in a fixed metallic collar, f, secured rigidly to the burner A. The lower end of this wiping-electrode is journaled 40 in a rotatable pulley, C, on one end of the gas-cock, the other end of which projects through the burner, and is held firmly in place by an adjustable split leaf-spring, s, taking behind a shoulder or groove, as shown.

45 d d is a cord or chain attached at a point on the upper surface of pulley C, the inwardly-projecting end of the wiping-electrode passing through said cord or chain, so as to hold it firmly in position. To the lower ends of the 50 cord or chain d d are attached two rods, l l', extending to the exterior of the protecting

candle-shield D through holes in the sustaining collar or ornament h, as clearly shown in Figs. 1 and 2. To the lower end of these rods are two ornamental chain cords, e e', with 55 knobs for manipulating them.

w is a conductor or wire running from one pole of the battery (not shown) to the stationary and insulated electrode b, the wiping-electrode being connected through the gas-pipe to 60 earth in the usual manner to the other pole of the battery.

The operation is as follows: Supposing the gas turned off and the apparatus in position shown in Fig. 1, taking hold of the lower 65 knob attached to chain e' and pulling downward, the pulley C is rotated to the left, and with it the gas-cock and the lower end of the wiping-electrode c. This turns on the gas, and at the same instant causes the wiping- 70 electrode to be lifted up and swung about its pivotal bearing in the collar f, thereby bringing it into sliding or wiping contact with the fixed electrode b and producing a spark, at the same time carrying it over and down out 75 of the flame in the reverse position from that shown in Fig. 1. On reversing the action by manipulating the cord e the gas may be turned off.

I am aware that it is old to unite an igniting 80 device to the cock of a gas-burner, so that by one action the gas is turned on and lighted, and that it is also old to provide gas burners or jets with imitation candle-shields in imitation of candles; but I believe it is new with 85 me to so combine these features as to make a neat, simple, cheap, and effective apparatus, being both novel and useful.

I am also aware that it is old in gas-lighting devices to combine a fixed electrode with a 90 vertically-sliding electrode and apparatus for operating the same by cord or chain, all of said parts being located inside of a protecting or concealing shield; but I am not aware that it is old to use an electric gas-lighter wherein 95 the electrodes, their operating mechanism, and the cock are all operatively connected and located inside a guard or shield which conceals and protects all of said parts.

What I do claim, and desire to secure by 100 Letters Patent of the United States, is—

1. In a gas-lighting device, a rotary cock

carrying a pulley to which is pivoted a rod or stem bearing a wiping-electrode, said rod or stem having a sliding fulcrum in a yoke or arm attached to a gas-burner, in combination 5 with a fixed electrode, also carried by the burner, and a manipulating cord or chain attached near its center to the pulley, substantially as described.

2. In a gas-lighting device, the combination 10 of a fixed and a wiping-electrode, the latter being pivoted to the gas-cock and having a sliding fulcrum or bearing through a fixed yoke or collar, substantially as described.

3. In a gas-lighting device, the combination of a fixed and a wiping electrode, the latter 15 being pivoted to the gas-cock and having a sliding fulcrum or bearing through a fixed yoke or collar, all of said parts being surrounded by a protecting or concealing shield, substantially as described.

DAVID ROUSSEAU.
